UNITED STATES PATENT OFFICE

WILLIAM F. WATKINS, OF OAKLAND, CALIFORNIA

SPARK-PLUG CLEANER

Application filed January 31, 1928. Serial No. 250,832.

My invention relates to improvements in sand blast spark plug cleaners and the object of my invention is to provide simple and efficient sand blast means for thoroughly removing the carbon from carbonized spark plugs very quickly and easily.

Another object is to provide a sand blast spark plug cleaner in which sand or salt or any other finely divided abrasive material may be employed, and, in which the abrasive material is returned to its original hopper and may be used over and over again many times thereby doing away with the necessity of replenishing the charge of abrasive material except at rare intervals.

Another object is to provide a sand blast spark plug cleaner by which clean air may be blown into the spark plug after the plug has been sand blasted, to thereby clean out all particles of sand and dirt.

A further object is to provide a spark plug cleaner that is adapted to receive and hold spark plugs of different size.

Other and more specific objects will be apparent from the following description taken in connection with the accompanying drawings.

In the drawings, Figure 1 is a view in side elevation of a sand blast spark plug cleaner constructed in accordance with my invention showing a spark plug therein.

Fig. 2 is a vertical mid-section of the same.

Referring to the drawings, throughout which like reference numerals designate like parts, 5 designates a sander body having, on its bottom, a cylindrical stud 6, that fits snugly but rotatably into the top end of a vertical supporting pipe 7 and serves to hold the sander body horizontal and to permit the sander to be adjusted by turning the same about a vertical axis. The lower end of the pipe 7 is secured by a fitting 8 to a support 10, as a bench or table.

The sander body is provided at its forward end with a receptacle 11 for a bushing 12 into which a spark plug 13 of the type commonly used in internal combustion engines is secured. The bushing 12 is held by readily releasable means, as by a set screw 14, so that it may be quickly and easily removed and re-

placed by a bushing of different internal diameter for the reception of a spark plug of different size. The sander body 5 is provided, just to the rear of the spark plug receptacle 11, with an internal upright tube or stand pipe 15 that extends through a bushing 16 into a sand receptacle 17, the stand pipe 15 constituting a part of the support for the sand receptacle 17. Within the rear end of the sander housing 5 is a suction chamber 18 of relatively large size into which extends a relatively small air jet tube 20 which is formed on the end of a bushing 21 that is screwed into the end of the sander housing 5. The suction chamber 18 has a convergent front end 22 and is provided with a small outlet opening 23 arranged directly in front of the end of the tube 20, the tube terminating a short distance from the opening 23. A valve 24 is connected with the bushing 21 and an air conduit tube 25 preferably a flexible hose, is connected with the valve 24 for supplying air under pressure to the sander. The top of the suction chamber 18 is connected by a passage way 26 through a valve 27 with the sand receptacle 17. The valve 27 has the usual valve plug 28 which may be turned to open or close the valve and said valve 27 cooperates with the pipe 15 in supporting the sand receptacle 17, a bushing 30 being provided in the bottom of the sand receptacle 17 to fit over the top of the valve.

A screen-like hood or cover, preferably in the form of a cloth bag 31 is slipped over the top of the sand receptacle 17 and secured in place by a snap ring 32. This bag is preferably of fine enough mesh to retain the finely divided abrasive material but is coarse enough to permit the air to escape freely without creating a back pressure. The tube 15 projects far enough up into the sand receptacle 17 to be above the sand that lies in the bottom of said sand receptacle.

In the operation of this spark plug sander, the spark plug 13 that is to be cleaned is screwed into the bushing 12 and the air valve 24 and sand valve 27-28 are opened, permitting sand to discharge into the suction chamber 18 and air under pressure to discharge at a high velocity from the end of the

5 tube 20. The discharging air creates a suction within the chamber 18, which picks up the sand and drives it forcibly against and into the end of the spark plug 13 thereby scouring the end of the spark plug and completely removing all carbon from the spark plug housing, and from the electrodes and the porcelain. I find that application of the sand for fifteen seconds is sufficient to remove all 10 carbon from the dirtiest spark plug leaving the porcelain absolutely white and the metal parts brightly burnished.

15 After the particles of sand strike against the spark plug they will be blown up through the tube 15 and will collect in the sand receptacle 17, the air escaping through the cover bag 31. After a spark plug has been sanded for about fifteen seconds the valve 27-28 is closed and the air valve left 20 open, allowing the air to blow all particles of dirt and sand out of the spark plug before the same is removed. The cloth bag may be readily removed and replaced if it becomes 25 badly worn by the sand. The sand or other abrasive may be used over and over again as long as any of the same remains.

30 The foregoing description and accompanying drawings clearly disclose a preferred embodiment of my invention but it will be understood that this disclosure is merely illustrative and that such changes may be resorted to as are fairly within the scope and 35 spirit of the following claims.

I claim:

35 1. In a sand blast spark plug cleaner, a sander housing, means at one end of said sander housing for receiving and holding a spark plug with its electrode end directed into said housing, means forming a chamber 40 at the other end of said housing, an air jet tube extending into said chamber and directed toward said spark plug, a receptacle for finely divided abrasive material, valve controlled conduit means for admitting abrasive material from the receptacle to the 45 chamber, and an upwardly directed return conduit for sand connecting said receptacle with said housing at a point adjacent the electrode end of said spark plug.

50 2. The apparatus as described in claim 1, in which the return conduit for sand projects upwardly into the sand receptacle above the usual sand level.

55 3. The apparatus as described in claim 1, in which the return conduit projects upwardly into the receptacle above the usual material level and a screen like cover is provided on the receptacle.

60 4. In a spark plug cleaner of the class described, a housing having a spark plug receptacle at one end and having a chamber toward its other end and having a relatively small opening between the chamber and the spark plug receptacle, means for supporting 65 said housing horizontally, a vertical con-

duit tube communicating with the spark plug receptacle, a valve communicating with said chamber and extending upwardly from the housing, a sand receptacle supported by said valve and said vertical conduit tube and communicating with both of the same, the tube extending upwardly into the sand receptacle above the usual sand level, a cloth bag forming a cover for the receptacle to prevent the escape of sand and permit the escape of air, an air jet tube extending into said chamber in alignment with said relatively small opening and valve controlled means for delivering compressed air to said tube.

70 75 The foregoing specification signed at Seattle, Wash., this 30th day of December, 1927.
